UNITED STATES PATENT OFFICE.

WILLIAM T. GELTZ, OF CLEVELAND, OHIO.

WORKMAN'S TIME-RECODER.

1,137,962.

Specification of Letters Patent.

Patented May 4, 1915.

Application filed March 15, 1913. Serial No. 754,587.

To all whom it may concern:

Be it known that I, WILLIAM T. GELTZ, citizen of the United States, residing at Cleveland, in the county of Cuyahoga and State of Ohio, have invented certain new and useful Improvements in Workmen's Time-Recorders, of which the following is a specification.

This invention relates to workmen's time recorders, and has for its object to provide an improved device or machine which will operate to register and record the elapsed time between any two periods.

The invention is particularly applicable to workmen's time recorders in which time is recorded on a card.

By means of the present machine the card will be marked with the starting and stopping times and will also compute and record on the card the elapsed time in hours and minutes between the start and the stop.

I am aware that machines have been proposed which will mark the times of starting and stopping a piece of work. With these machines it is necessary for the bookkeeper to figure the elapsed time. The present machine does this automatically, and will mark the elapsed time on the record card.

The invention is illustrated in the accompanying drawings in which—

Figure 1 is a front view of the machine, parts being broken away. Fig. 2 is a side view of the same. Figs. 3, 4 and 5 are details of the wheels which drive stencil belts. Fig. 6 is an enlarged detail of the working mechanism. Fig. 7 is a detail of a modified form of stencil or marking belt, using linked plates instead of a continuous belt. Fig. 8 is a detail in section of a sliding pin point used to connect two of the wheels. Fig. 9 is a detail in section of one of the wheels, showing a spring pawl. Fig. 10 is a view of a card showing a starting record. Fig. 11 is a similar view showing the complete record.

Referring specifically to the drawings 6 indicates a clock having a proper escapement which controls the turn of a shaft 7 geared by bevel gears 8 and 9 to a first wheel 11 mounted to turn on a fixed shaft 22. This wheel 11 is the standard time wheel and is always synchronous with the clock movement. It is not driven by the clock movement, but is retarded thereby, being driven by other means to be described, and

acting to jump forward at intervals of one minute each by means of the clock escapement.

On the side of the wheel 11 adjacent to the second wheel 14, the said wheel 11 is provided with a spiral groove 12, beginning at the hub and ending at the stop J near the periphery. The second wheel 14, also mounted to turn on the shaft 22, is the driving wheel. It is driven by gearing 27 meshing with the peripheral gear 15, from a spring motor 28 which may be of any suitable type. It turns the wheel 14 forwardly, and this wheel 14 carries a chisel pin 13 which travels in the groove 12, and so carries the wheel 11 forwardly, by contact of said pin with the stop J, as fast as permitted by the clock escapement. The chisel pin 13 is mounted in a radial groove 13^a in the wheel 14, so that it can move from one end to the other of said groove and thus follow the windings of the spiral groove 12 when the wheel 14 is turned backwardly with respect to the wheel 11. This chisel pin 13 is mounted on the side of the wheel 14 adjacent the wheel 11. On the opposite side of the wheel 14 is carried a pawl 23 pressed by a spring 24 and arranged to engage in a ratchet 25 on the side of the third or elapsed time wheel 26, the ratchet having sixty teeth corresponding to the minutes in an hour, and so presented that when the wheel 14 is turned forwardly the pawl 23 will slip over the same without moving the wheel 26, but when the wheel 14 is turned backwardly to take a "finish" record the pawl 23 catches in the ratchet and turns the wheel 26 back as many minutes as the wheel 14 is turned back. The wheel 14 is geared by a gear wheel 27, and suitable gears 16^a, to an indicator 17, of known construction, which simply serves to indicate the number of minutes the wheel 14 is turned back. On the outer side of the wheel 26 (which wheel is also loose on the shaft 22) is a groove exactly similar to the groove 12 on the wheel 11, and in this groove there is also a chisel pin 29 which stops against the end of the spiral groove and prevents the wheel 26 from going forward past the zero point, but permits the wheel 26 to be turned back. The chisel pin 29 is slidably mounted on a support 31 attached to the shaft 22, said support permitting radial movement of the chisel pin. The wheel 26 is normally held at zero or

normal position by means of a spring 30 which returns said wheel to zero position after each operation.

20 is a crank shaft extending through a bore in the shaft 22, and provided at its outer end with a crank handle 21 located outside the casing. At its inner end this shaft has a gear 19 meshing with an internal gear 18 in the hub of the wheel 14. A spring 32 normally pushes the gear 19 out of engagement, but when the shaft 20 is pushed in, as shown in Fig. 6, the gears engage, and by turning the crank 21 the wheel 14 may be turned back, carrying with it the wheel 26 by means of the pawl 23 and the ratchet 25, as above described.

Each of the wheels 11, 14 and 26 operate suitable marking devices. I have shown stencil bands A, driven by each of these wheels, and passing over pulleys B in position to permit a card inserted in the holder C to be marked. This marking will be effected in any suitable way, preferably by the means shown and described in my pending application Serial No. 748913, filed February 17, 1913, and indicated as a whole at D, and acting as described in said application to blow ink through the stencil openings of the belts onto a card inserted in the holder, as fully described in said application; or a marking brush may be used, as also described in said application. Instead of a continuous stencil belt, a belt of stencil plates 33, containing successive minute marks or openings, and connected by links 34, may be used. Or various other types of printing devices may be used, within the scope of the invention.

In operation, the wheels 11 and 14 turn and advance the belts thereon minute by minute as permitted by the clock escape-
40 ment, thus indicating the standard time; and the wheel 26 remains idle or at zero. Assuming that a workman comes at 1 o'clock to mark the start of a job, he inserts his card 45 in the holder and by operating the marking mechanism the card receives the following marks:

Start 1:00 1:00 0:00

50 These marks being made respectively by the belts carried by the wheels 11, 14 and 26 respectively, the last always recording zero at the start. Assuming that the job is finished at 3:26, the workman inserts his card and 55 by means of the crank 21 (which he pushes in to engage the gears 18 and 19) he turns back the wheel 14 until the register 17 shows the starting time, or 1 o'clock, thus indicating that the wheel 14 has been turned back 60 a period of time equal to the elapsed time on the job. As the wheel 14 is turned back it carries with it the wheel 26, also the same period of time. During this movement, the chisel pin 13 travels in the groove 12, and 65 the chisel pin 29 travels in the similar groove

on the wheel 26. Then by operating the marking mechanism the card is marked as follows:

Stop 3:26 1:00 2:26

The first being the mark on the belt on the wheel 11; indicating the standard time, 3:26, the job was stopped, the second being a "proving" mark indicating that the wheel 14 was turned back to the same extent it had 70 been turned forward in time, and the third mark, 2:26, being the elapsed time, printed by the belt carried by the wheel 26. The crank 21 is then pulled out and released, and the wheel 26 is turned to zero by the spring 80 30, and the spring motor 28 turns the wheel 14 forwardly until the chisel pin 13 strikes the stop J, thereby bringing the wheels 11 and 14 into synchronism, ready for the next 85 operation.

It will be seen that by means of the start and stop records the standard times of starting and stopping is shown, also the elapsed time, and the correctness of the latter is proved by the similarity of the two marks 90 given by the middle wheel 14.

The invention is not limited to the exact embodiment shown, but various modifications may be used, within the scope of the following claims. The groove 12 is long 95 enough to permit the second wheel to be turned back an extent equal to twelve hours, say, or at least a full working day.

By this invention it is impossible to take an incorrect registration without instantly 100 showing not only that a mistake has been made but the extent of the time thus added or taken.

What I claim is:

1. In a workmen's time recorder, the combination of a clock controlled standard time wheel, driven in one direction, a proving wheel driven forwardly simultaneously an extent equal to the standard time, an elapsed time wheel, means to turn the proving wheel 105 backwardly to an extent equal to the forward movement, means engaging between the proving and elapsed time wheels to turn the latter to an equal extent when the former is turned backwardly, and marking means 110 carried by each of said wheels.

2. In a workmen's time recorder, the combination of a clock controlled standard time wheel movable forwardly, a motor driven proving wheel provided with a device having a driving engagement with the standard time wheel when the proving wheel is turned forwardly, whereby the standard time wheel is turned by the proving wheel forwardly, an elapsed time wheel normally held at zero, 115 120 manually operated means to disengage the proving wheel from the motor and turn the same backwardly an extent equal to its forward turn, means engaging between the proving and elapsed time wheels to turn the latter 125 130

to an equal extent when the proving wheel is turned backwardly, and time marking means carried by each of said wheels.

3. In a workmen's time recorder, the combination of a standard time wheel, a clock mechanism controlling the same, said wheel having a stop, a proving wheel having a device engaging said stop in one direction, whereby the wheels turn equally in said direction, driving means to turn said proving wheel in said direction, manually operated means to turn the proving wheel in reverse direction to an equal extent, an elapsed time wheel normally held at zero position, means engaging between the proving and elapsed time wheels to turn the latter equally when the former is reversed, time-marking means operated by each of said wheels, means to return the proving wheel until the device carried thereby strikes the stop when said manually operated means are released, and means to simultaneously return the elapsed time wheel to zero position.

25 4. In a workmen's time recorder, the combination of a clock controlled standard time, adapted to be driven in one direction, a proving wheel adapted to be driven to an equal extent in said direction, means to drive said wheels in said direction, an elapsed time wheel normally at zero position, means to turn the proving wheel in the opposite direction to an extent equal to its movement in said direction, a time indicator geared to the proving wheel, to indicate the extent of said reverse turn, means engaging between the proving wheel and the elapsed time wheel to turn the latter to an equal extent when the former is turned in said reverse direction, and marking means actuated by each of said wheels.

5. In a workmen's time recorder, the combination of a clock controlled first wheel provided on one side with a spiral groove, a motor driven second wheel located beside said first wheel and provided with a pin adapted to travel in said groove and stop against the end thereof and thereby turn the first wheel to an extent equal to the turn of the second wheel in one direction, means to turn the second wheel in reverse direction, a third wheel mounted beside the second

wheel and normally held in zero position, pawl and ratchet mechanism engaging between the second wheel and third wheel 55 and adapted to turn the latter equally with the former when said former is turned in reverse direction, and marking means operated by each of said wheels.

6. In a workmen's time recorder, the combination of a clock controlled first wheel provided on one side with a spiral groove, a motor driven second wheel located beside said first wheel and provided with a pin adapted to travel in said groove and stop 60 against the end thereof and thereby turn the first wheel to an extent equal to the turn of the second wheel in one direction, means to turn the second wheel in reverse direction, a third wheel mounted beside the second wheel 65 and normally held in zero position, pawl and ratchet mechanism engaging between the second and third wheels and adapted to turn the latter equally with the former when said former is turned in reverse direction, 70 and a belt driven by each wheel and provided with marking means adapted to make a time record.

7. In a workmen's time recorder, the combination of a shaft, a clock controlled first 80 wheel mounted to turn thereon, a second wheel mounted to turn on the shaft beside the first wheel, a driving device engageable between the first wheel and the second wheel when the latter is turned in one direction, 85 means to turn the second wheel in said direction, a manually operated, crank shaft mounted in said shaft and having a gear engageable with the second wheel to turn the latter in reverse direction, said crank 90 shaft being shiftable lengthwise to engage or disengage the gear, a third wheel mounted on the shaft beside the second wheel, driving devices between the second wheel and the third wheel engageable when the 95 former is turned in reverse direction, and time marking means operated by each of said wheels.

In testimony whereof, I do affix my signature in presence of two witnesses.

WILLIAM T. GELTZ.
